CLOTHES RACK OR SIMILAR ARTICLE

Alfred E. Hembd and Paul E. Hembd,
Arlington Heights, Ill.

Application March 2, 1959, Serial No. 54,810

Term of patent 3½ years

(Cl. D33—8)

Fig. 1 is a view in perspective of the clothes rack or similar article;

Fig. 2 is a side elevational view of the upper section of Fig. 1, taken along the line 2—2 of Fig. 1, looking in the direction of the arrows;

Fig. 3 is a horizontal sectional view of the lower section of Fig. 1, taken along the line 3—3 of Fig. 1, looking in the direction of the arrows;

Fig. 4 is a fragmentary top plan view, taken along the line 4—4 of Fig. 1, looking in the direction of the arrows.

We claim:

The ornamental design for a clothes rack or similar article, as shown.
